ATTORNEY.

UNITED STATES PATENT OFFICE

JOHN DAHL, OF DALLAS, TEXAS, ASSIGNOR TO DAHL BIT CORPORATION, OF DALLAS,
TEXAS

DRILL BIT

Application filed June 15, 1928. Serial No. 285,521.

This invention relates to well drilling tools and it has especial reference to certain new and useful improvements in drill bits of the type wherein a continuous stream of water is injected into the hole being drilled, for proper lubrication of the bit in operation, and the principal object of the invention resides in the provision in such a bit of a means to reduce materially the friction created by passage of water and slush under pressure through the water courses in the body of the bit, and to thus increase the longevity and consequent usefulness of the tool.

The invention has for another object to bring about in such a means as aforesaid, a considerable reduction in the strain upon the pressure pump employed to circulate water in the hole, by minimizing friction in the bit, and in so doing, prolonging the life of the pump and increasing its efficiency.

Still further, the invention aims to provide means which are interchangeable and replaceable when same become worn by the contact of sand and other cutting substances passing at high velocity which becomes mixed with water under pump pressure.

With the foregoing objects as paramount, the invention has particular reference to its salient features of construction and arrangement in the bit, to become manifest as the description proceeds, taken in connection with the accompanying drawings, wherein:—

Figure 1 represents a side elevational view of a bit in which the invention is incorporated, parts being broken away to better illustrate the same.

Figure 2 is an end section on line 2—2 of Figure 1.

Figure 3 is a fragmentary view in section of a modified example of the invention, and

Figure 4 is a detail view of one of the interchangeable bushings.

Continuing now more in detail with the drawings, reference is primarily made to Figure 1 in which an improved type of bit is illustrated, the body 1 of which is formed with shoulders 2 set at such an angle as to allow for rapid circulation of water, and to direct the same upward, past the shank 3 without interference thereby to retard its progress.

This bit is further provided with interchangeable cutting blades 4, which are so disposed in the head as to insure maximum cutting efficiency.

It will be understood however, that the specific construction of the bit shown does not in any way restrict the use of the invention to be presently described in detail, as the invention is adapted for application to any type of earth boring tool employing the circulation of fluid as a lubricating medium.

Accordingly, the invention consists primarily in providing a cavity 5, cored out of the shank 3, which is for the purpose of materially shortening the water courses 6, drilled downward and outward from the bottom of this cavity to a proper point for discharging fluid on the operative surfaces of the blades 4. In so shortening the water courses, much friction is obviated in passing fluid therethrough, and the attendant danger of stopping or plugging the courses is minimized. When the water courses in a bit are plugged by accumulation of substances therein, it is obviously necessary to withdraw the bit from the hole, with the added disadvantage of having to lift the column of water entrapped in the drill stem assembly and requiring that such water be released on the derrick floor, creating an annoying and hazardous condition. To so reduce the likelihood of plugging the water courses in the bit is obviously an important feature in bit construction.

Fluid passing through the courses 6 often attains a pressure of 1000 pounds and such pressure, if unduly retarded brings about an enormous strain upon the pump, and when possibilities of plugging are removed, normal and efficient performance of the pump is assured, obviously also, adding to the life of the pump.

Passage of water through the courses 6 at such high velocity, and carrying with it quantities of sand and other similar substances, finally wears upon the walls of the passages to such an extent as to impair the efficiency of the head and it is often necessary to dispense with the tool prematurely. To obviate this disadvantage and expensive practice, the

courses 6 are provided with bushings 7 of steel or its equivalent and, as shown in Figure 4, are provided with an annular shoulder 8 about the tops which shoulder prevents the tubular bushing from passing through the passage. These bushings are merely inserted into the passages from the top ends and are not required to be fastened except possibly by making a snug fit. However, in order to aline the lower ends of the bushings, which are obliquely cut to correspond with the exterior surface of the bit stock, a protuberance 9 is formed underneath the annular shoulder 8 of the bushing, which enters a corresponding recess in the top edge of the passage, as shown in Figures 1 and 4.

With especial reference to Figure 3, a modified showing, instead of providing a straight cavity as in Figure 1, the passages 10 are drilled in the shank 3 at angles with respect to the axis of the body 1, and are substantially funnel shaped. In forming the courses thus, even less friction is encountered as the fluid does not have to contact with a flat surface, but may pass unrestrictedly through the passages to the outside walls of the body.

In order to remove the bushings 7 from the passages 6, it is required simply to insert a suitable tool in the lower end of the passage, and drive the bushing upward.

What is claimed is:—

In a drill bit, a shank having angular bores and bushings in the bores having circular outwardly extending flanges on their upper ends and having depending projections on the under faces of the flanges, the bushings having their lower ends bevelled to lie flush with the periphery of the shanks, the bores at the upper ends thereof having lateral recesses to receive the projections, the recesses and projections being located and related so that when the projections lie in the recesses the bevelled ends of the bushings are held flush with the shank.

In testimony whereof I affix my signature.
JOHN DAHL.
